UNITED STATES PATENT OFFICE.

LOUIS DIEFENBACH, OF UNION HILL, NEW JERSEY.

JACQUARD CARD-WIRE.

No. 872,910.

Specification of Letters Patent.

Patented Dec. 3, 1907.

Application filed April 8, 1907. Serial No. 366,904.

To all whom it may concern:

Be it known that I, LOUIS DIEFENBACH, a citizen of the United States, residing in Union Hill, county of Hudson, and State of New Jersey, have invented certain new and useful Improvements in Jacquard Card-Wires; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 My invention relates to devices, known as card wires, employed to support on races the cards of a jacquard or other similar machine in the interims between their passing over the cylinder of the machine.

20 The object of the invention is to provide a card wire which, while possessing in itself means for securing it against endwise play when operatively attached to a series of cards, will be comparatively little more, if 25 any more, expense to manufacture than the plain straight card wire now in common use, secure against becoming detached from the cards, and capable of being applied to the cards so that either side thereof may be presented to the cylinder.

30 The invention will be found fully illustrated in the accompanying drawings, wherein,

Figure 1 shows several cards laced together and one of the improved card wires attached thereto; Fig. 2 is a perspective view of the card wire showing the manner in which it engages the lacing; Fig. 3 is a view illustrating the card wire as it rests on the cylinder, the lacing being shown in section; and, Figs. 4 and 5 are a plan view and a side view, respectively, of the card wire.

In the drawings, *a* designates the cards, *b* the cylinder having the pegs *c* which engage 45 with the holes *d* in the cards to cause the advancement of the series of cards, and *e* the usual lacing between the cards.

f designates the improved card-wire. This is preferably a plain piece of wire having 50 its end portions bent so as to form hooks or crotches *g* opening toward each other for the reception of the lacing and projections *h* extending beyond said hooks so as to serve to support the wire on the race (not shown).

55 Said hooks or crotches and projections are produced as follows: The end-portions *i* of

the wire are bent first back on themselves in the same plane and parallel with the body-portion *k* of the wire in such manner as to leave narrow spaces *l*, each space being accessible only from the inside, *i. e.*, from the direction of the further end of the wire. Said end-portions are then again rebent, preferably both in the same direction with respect to the body portion of the wire, this 60 time outwardly and in a plane at right angles to the plane occupied by said body-portion and the first rebend. The bending of the wire is so accomplished that the extremities thereof project, after the second bending, beyond the hooks or crotches *g* so as to form the projections *h*. The second rebends are shown in the drawings as formed so that no spaces are left, such as the spaces *l*; though this is not absolutely essential. 75

In assembling the wires and the laced cards, one hook of each wire is slipped over the lacing between cards and then the two cards are bent somewhat, transversely, until the lacings are brought closely together 80 enough so that the other lacing may be in like manner entered into the other hook. The hooks should be spaced apart sufficiently so that the two lacings will abut nicely against the hooks when entered therein and thus keep the wire against endwise movement. When thus assembled with the cards the wires stand in such position with relation thereto that the cards are opposite the spaces *l* formed by the hooks and, owing 90 to the fact that each wire is bent in the peculiar manner above described, its body-portion and the projections *h* will be in planes on opposite sides of the plane occupied by the cards and lacings and equidistant from said 95 plane. The advantage of this feature is that the wires may be used indifferently either side up, *i. e.*, the body-portions above and the projections below the lacings, or vice versa, and whether they are in the one position or the other the lacings come the same distance from the face of the cylinder as the wires are passing over the latter and the cards engage the pegs on the cylinder at the same elevation. If the projections were arranged in a plane which was further from that of the lacings than the plane of the body-portions of the wires, the wires could not be used either side up without either making 100 the pegs unduly long or having to contend 105 with the cards more or less frequently slipping over the pegs.

Having thus fully described my invention, what I claim and desire to secure by Letters Patent is:

1. A jacquard card-wire having hooks near its ends opening toward each other and projections extending beyond said hooks, each projection and the portion of the wire connecting said hooks being offset relatively to each other and substantially equidistant from a plane which intersects that of the corresponding hook at right angles thereto and is disposed in the axial line of the space of said hook, substantially as described.
2. A jacquard card-wire having a substantially straight body portion and its end-portions rebent first toward each other and forming open hooks and then rebent away from each other, the extremities of the wire

being projected beyond the hooks to form the supporting portions of the wire, substantially as described. 20

3. A jacquard card-wire having a substantially straight body-portion and its end-portions rebent first toward each other and forming open hooks and then rebent away 25 from each other, the two rebends being disposed in planes intersecting each other, substantially as described.

In testimony, that I claim the foregoing, I have hereunto set my hand this 5th day of 30 April, 1907.

LOUIS DIEFENBACH.
